United States Patent Office

Des. 223,660
Patented May 23, 1972

223,660

BUILDING STRUCTURE

Glen C. Hancock, Sarasota, Fla., and Wilmer Terry Young, Charlotte, N.C., assignors to Shoney's South, Inc., Memphis, Tenn.

Filed Oct. 6, 1970, Ser. No. 25,358

Term of patent 14 years

Int. Cl. D25—03

U.S. Cl. D13—1

FIG. 1 is a top plan view of a building structure embodying our novel design;

FIG. 2 is a front elevational view of the building structure taken along line 2-2 in FIG. 1;

FIG. 3 is a side elevational view of the building structure taken along line 3-3 in FIG. 2;

FIG. 4 is a rear elevational view of the building structure taken along line 4-4 in FIG. 3; and

FIG. 5 is a side elevational view of the building structure taken along line 5-5 in FIG. 4.

We claim:

The ornamental design for a building structure, substantially as shown and described.
